5 Claims. (Cl. 80—14)

This invention relates to the manufacture of seamless metal tubes. More especially it is concerned with improvements in the control of pilger mill operations.

In known pilger mill procedures, a heated open-ended cylindrical hollow or tube blank is placed on a mandrel and worked thereon between driven grooved rolls having a peripheral gap. Under the action of the rolls, the mandrel is forced backward against resilient means, thereby compressing the latter, and when the gaps in the rolls come round to the blank in the revolution of the rolls, they release the grip of the rolls so that the resilient means reacts to return the mandrel. During this time, the resilient means and the mandrel are fed steadily forward together to move up a fresh part of the blank for treatment by the rolls, the various operations being repeated until the treatment of the blank is completed. Provision is made to soften the arrest of the parts suddenly moved forward under the reactive impulse of the resilient means. Suitably, a sort of dash-pot arrangement is used. Nevertheless, a considerable impact blow is experienced which adversely affects steady forward feed of the blank. Arrangement is made, therefore, for this impact blow to be transmitted to hydraulic piston and cylinder apparatus causing the hydraulic medium in this apparatus to be increased in pressure intensity. Restricted orifice release of the medium from such apparatus is provided for to control the forward feed of the blank, that is to say the steady feed of the mandrel in company with the resilient means as aforesaid. Moreover, it is known that the impact blow referred to tends to increase the restricted orifice outflow of the medium from the hydraulic piston and cylinder apparatus. The amount of this outflow at this time would permit feed of the blank at increased velocity were it not for the fact that the resistance of the hydraulic piston and cylinder apparatus is arranged to be greater than the force, usually hydraulic, provided for that feed. The increased pressure intensity induced in the hydraulic medium as stated, is of extremely short duration and owing to this, and to the inertia of the hydraulic mass in the hydraulic piston and cylinder apparatus being relatively great, this apparatus rebounds, or tends to rebound, after the impact blow has been imparted at the dash-pot. Consequently, the feed means for the blank becomes arrested in its operation, or is slowed down. Or sometimes, this means will be forced back. As a result, the desired constant increment of feed distance of the blank per revolution of the pilger rolls has been difficult, if not impossible, to attain. Sometimes, a mechanical control, such as a screw and a co-operative nut which is rotated at a speed suitably synchronised with the speed of the pilger rolls, is provided to cause the feed means to move the blank forward by a pre-determined distance per revolution of the pilger rolls. Such mechanical control, however, creates much difficulty because of the heavy wear to which it becomes subjected, and because of the great frictional heat generated because the nut and screw, as a result of the heavy loads imposed thereon.

An object of the present invention is to provide a simple and reliable method of, and apparatus for, obtaining a constant amount of forward movement of the blank per revolution of the pilger rolls.

According to one feature of this invention, a method of manufacture of seamless metal tubes by pilger rolling wherein the impact blow, resulting from the sudden forward movement of the mandrel, under the reactive impulse of resilient means previously stressed during the rolling, is transmitted to hydraulic piston and cylinder apparatus, is characterised by the step of releasing hydraulic medium from said hydraulic piston and cylinder apparatus in substantially precisely determined quantity per revolution of the pilger rolls.

According to another feature of the present invention, a pilger mill for the manufacture of seamless metal tubes and comprising peripherally grooved and gapped rolls, a carriage supporting resilient means comprising a part which is movable forward and backward on the carriage and supports the mandrel and a companion part which is fixed relatively to the carriage, means for forward feed of the carriage, and hydraulic piston and cylinder apparatus to which an impact blow on the carriage, as a result of sudden forward movement of the mandrel by reactive impulse of the resilient means, is transmitted when the gaps in the rolls come round to the blank on the mandrel, is characterised by a second hydraulic piston and cylinder apparatus having connections with the one first-mentioned so as to receive hydraulic medium through said connection during forward feed of the carriage, and means operative to determine substantially precisely the stroke of said second hydraulic piston and cylinder apparatus, whereby the amount of feed of the tube blank per revolution of the pilger rolls may be maintained substantially constant.

The method of the invention may be carried out in such a way that any overstepping of the determined quantity of hydraulic medium released from the first hydraulic piston and cylinder apparatus due to the effect of the impact blow referred to, may be taken up so that the determined quantity, in the net result, is maintained substantially constant.

For this purpose, the apparatus may further comprise means whereby the piston and cylinder components of the second hydraulic piston and cylinder apparatus may be further displaced relatively to each other at the end of the determined stroke against the action of yieldable means operative to counteract the displacement. This yieldable means may be of the nature of a spring or of a constant pressure pneumatic or hydraulic piston and cylinder apparatus.

In order to enable the invention to be readily understood, reference is directed to the accompanying drawings in which:

Figure 1 is a sectional elevation of one example of apparatus constructed in accordance with, and operative according to the method of, the present improvements,

Figure 2 is partly a plan view of the apparatus and partly a sectional elevation of the second hydraulic piston and cylinder apparatus thereof, and

Figure 3 is a fragmentary plan view illustrating a modification.

The apparatus shown in Figures 1 and 2, comprises a sole plate 10 fixed to the ground and a carriage 11 mounted to slide forward and backward on the upper face of the sole plate and between guides 12 lying along each side of such plate. A hydraulic cylinder 13 is disposed at the rear end of the sole plate 10 between a block 14 at that end and a fixed support leg 15 further back. The piston 16 of the cylinder 13 is connected to the rear end of the carriage 11 so that the cylinder, here-

inafter termed the feed cylinder, and its piston are operative to move the carriage forward. Rearward movement of the carriage is effected by a hydraulic piston and cylinder apparatus which suitably comprises a pair of cylinders 17 disposed one along each side of the sole plate 1 above the respective guides 12 aforesaid. The pistons 18 of the cylinders 17 are connected at their rear ends to a cross-head 19 on the carriage 11. The upper part of the carriage is formed, forward of the cross-head, with an air chamber 20, and forward of that with a water brake chamber 21. Rearward of the cross-head 19 the carriage 11 has fixed thereon a pedestal 22 housing a ratchet wheel 23 with multiple sets of teeth, the pedestal carrying a corresponding set of ratchet pawls 24. The ratchet wheel 23 is revoluble in bearings in the pedestal 22 and is fixed to a shaft 25 which extends forwardly through the cross-head 19 and into the air chamber 20 wherein it is slightly enlarged and formed with helical grooves at 26. The helically grooved part 26 engages in a correspondingly grooved nut 27 fixed within the rear end of a hollow piston 28 which has an external frusto-conical shoulder 29 at its forward end. From this shoulder the piston is extended as a solid shaft 30 to a mandrel head 31 slidable on the carriage 11 between guides 32. Forwardly of the mandrel head the shaft 30 is formed for connection to the rear end of a mandrel 33 and carries a stripper block 34 for use in stripping completed tubes from the mandrel. Forwardly of the sole plate 1 is a pair of peripherally grooved pilger rolls 35 gapped at one part of the periphery in the well-known manner as at 36. A more or less cylindrical recess 37, suitably slightly tapered as shown, is formed at the forward end of the water chamber 21 to serve as a sort of dash-pot for the shouldered forward end 29 of the hollow piston. This recess 37 is suitably provided in a liner 38 presenting a companion abutment shoulder to the shoulder 29 on the hollow piston. When, in the operation of the pilger rolls 35 on a blank such as 39, disposed on the mandrel 33, the latter is forced back, the hollow piston 28 moves over the helically threaded part 26 of the ratchet-wheel shaft 25, and the nut 27 in the rear end of the piston co-operates with the threads to cause the piston and the ratchet wheel 23 to revolve so that a fresh part of the periphery of the blank 39 is brought into position to be worked by the rolls, the ratchet pawls 24 ensuring that this rotation is in one direction only. The rearward movement of the hollow piston 28 causes the air in the piston and in the air chamber 20 to be compressed and the piston 28, air chamber 20 and helically grooved part 26 of the ratchet-wheel shaft 25 together constitute what is known in the art as "resilient means." When the gaps 36 in the pilger rolls 35 come round to the blank 39, the grip on the blank is released and the hollow piston 28 and its shaft 30 are moved forward under the reactive force of the air compressed in and by the hollow piston. The movement is sudden and the dash-pot 37 serves to brake it towards the forward end of the stroke. Nevertheless, an impact blow of considerable force comes on to the carriage 11 when the shouldered part 29 of the piston 28 reaches the corresponding shoulder in the forward end of the dash-pot. This impact blow is transmitted through the cross-head 19 to the pistons 18 of the hydraulic piston and cylinder apparatus 17, 18 which also serves to return the carriage 11 to its original position. During this return movement, the blank 39 is stripped from the mandrel 33 by the stripper block 34 after the well-known manner. Independently of the forward movement of the blank 39 with the mandrel 33 under the reactive impulse of the resilient means, the mandrel and resilient means are fed forward together with the carriage 11 by the hydraulic feed cylinder 13 and piston 16 and, of course, appropriate controls are provided for this hydraulic operation.

The pilger mill construction as thus far described provides for operations of a nature well understood in the

art. In accordance with the present invention, a second hydraulic piston and cylinder apparatus 40 is provided on a bed plate 41 fixed to the ground. This apparatus comprises a pair of cylinders 42, 43 oppositely disposed on a common axis and having communications at their inner ends, through suitable hydraulic connections 44, 45, 46 and a change-over valve 47 and an adjustable stop valve 48, with a junction box 49 connected by appropriate piping 50 with the inner ends of the cylinders 17 of the first-mentioned hydraulic pistons and cylinder apparatus 17, 18. The terms first and second hydraulic apparatus will be used for convenience to designate the two hydraulic piston and cylinder apparatuses 17, 18 and 40 respectively. The piston 18 of the first hydraulic apparatus 17, 18 are connected to the cross-head 19 as above stated. The pistons 52, 53 of the second hydraulic apparatus 40 are joined at their outer ends by an abutment member 51 slidable on the bed plate between two abutment surfaces 54, 55. The cylinders 42, 43 of this second hydraulic apparatus 40 also are slidably mounted on the bed plate 41 each between abutment surfaces 56, 57, but each is normally held against one abutment 56 by the pressure exerted by a compression spring 58 carried by the cylinder slides 59 or 60 and bearing on the other abutment 57. If desired the compression springs 58 may be substituted by constant pressure pneumatic or hydraulic piston and cylinder apparatus as will be understood. The travel of the abutment member 51 is determined by the thickness of a packer 61 inserted against one or the other of the corresponding abutment surfaces 54, 55 (as shown, the abutment surface 55). Hydraulic pressure is transmitted to the cylinders of the second hydraulic apparatus from the cylinders of the first hydraulic apparatus through the junction box 49 and connections and valves aforesaid. The change-over valve 47 operates to connect the cylinders 42, 43 of the second hydraulic apparatus alternatively to the cylinders 17 of the first hydraulic apparatus and to the exhaust connection 62.

In the operation of the mill, assuming a blank 39 to be applied to the mandrel 33 and the pilger rolls 35 to be operating in normal manner, as hydraulic medium is supplied to the feed cylinder 13 to move the carriage 11 forward, together with the resilient means, to feed a fresh part of the blank into the rolls, hydraulic medium in the cylinders 17 of the first hydraulic apparatus is forced out through the piping 50 and the movement of this medium is transmitted through the junction box 49 and the connection 46 and appropriately adjusted stop valve 48 and the change-over valve 47 to one or the other of the cylinders 42, 43, of the second hydraulic apparatus 40 according to the setting of the valve. The piston 52 or 53 of the latter cylinder is thus forced outwardly and it is so forced a distance determined by the movement of the abutment member 51. This distance, as already indicated, depends on the thickness of the packer 61 aforesaid. Packers of different thicknesses are provided and the thickness of the packer immediately in use is determined by the increment of feed desired for the size and weight of blank being milled. Appropriately, the abutment 55 against which the packer is placed may be used to determine the distance which the abutment travels in one particular case, packers of suitable thicknesses being used at 61 for other cases. In any case, the distance is one which has previously been precisely determined as will be understood. The second hydraulic apparatus 40, in effect, provides a measuring medium for determining the amount of hydraulic medium discharged from the first hydraulic apparatus 17, 18.

When the piston of the second hydraulic apparatus 40, in action, has carried the abutment member up to the packer 61, or the adjacent abutment 55, or to the other abutment 54 if the piston is being moved toward that abutment, the travel of the feed cylinder piston 13, and thus the travel of the carriage 11, ceases and it does so

until the gaps 36 of the pilger rolls 35 come round to the blank and release the aforesaid resilient means. When that happens, the hollow piston 28 of the resilient means shoots forward through the water chamber 21 on the carriage 11 and its shouldered end 29 enters the dashpot 37. This brakes the reciprocatory parts and terminates in an impact blow on the shoulder of the dash-pot device. This blow, however, is transmitted through the cross-head 19 to the pistons 18 of the first hydraulic apparatus 17, 18.

Since the piston 52 or 53 of the second hydraulic apparatus 40, however, will have already reached the full limit of its travel in its cylinder 42 or 43, any increase in hydraulic pressure intensity in the cylinders 17 of the first hydraulic apparatus, following the impact blow transmitted to the pistons 18 of the latter apparatus, will cause the cylinder 42 or 43 respectively of the piston and cylinder combination 42, 52 or 43, 53 of the second hydraulic apparatus 40 to move along its slide surface on the bed plate 41 and compress the spring 58 (or equivalent pneumatic or hydraulic apparatus) against which the movement of such combination will take place. This will allow the pistons 18 of the first hydraulic apparatus to move forward slightly, as well as the carriage 11 and the feed cylinder piston 16. This movement, of course, must not be greater than an appropriate extent determined by the movements of feed given to the blank 39. It can be determined by an adjustable stop or by suitable packers or restraining bolts as will be realized.

After the dissipation of the energy resulting from the impact blow, the compression spring 58 (or equivalent pneumatic or hydraulic apparatus) will return the cylinder 42 or 43 as the case may be so that a small quantity of hydraulic medium will be returned from this cylinder 42 or 43 of the second hydraulic apparatus 40 to the cylinders 17, of the first hydraulic apparatus. This will cause the pistons 18 of the latter apparatus to move back slightly and, correspondingly, the carriage 11 and its feed piston 16. The net feed increment of the blank 39 per revolution of the pilger rolls 35 will therefore be precisely that determined by the initial movement of the immediately operative piston of the second hydraulic apparatus 40.

Suitably, the above return of each cylinder of the second hydraulic apparatus 40, is made to actuate an electronic device (not shown) which, acting to control an electric solenoid (or a thruster), operates the change-over valve 47 so that each cylinder of this second hydraulic apparatus is used in turn.

For the purpose of enabling the first hydraulic apparatus 17, 18 to move the carriage 11 backward to its original position and to effect stripping of the tube 39 from the mandrel 33, provision is suitably made for high-pressure hydraulic medium to be admitted to the aforesaid junction box 49, and thus to the inner end of the cylinders 17 of this hydraulic apparatus, through a hydraulic connector 63 under control of a valve 64. At this time, the adjustable stop valve 48 in the hydraulic connections 46 to the second hydraulic apparatus 40 would be closed.

It will be realized that, by the invention, in spite of the impact blow referred to, substantially constant increments of feed of the blank into the rolls of the pilger mill is obtained with considerable advantage in the pilger mill operations. Greatly improved consistency in the amount of material of the blank to be fed to the pilger rolls at each revolution of the rolls is obtained as will be understood.

As illustrated in Figure 3 the second hydraulic apparatus 40 may have the pistons and cylinders duplicated, i. e. comprise oppositely arranged pairs of hydraulic

pistons 52a, 53a and cylinders 42a, 43a. The abutment member 57a in that case would suitably have the nature of a cross-head connected across the ends of the pistons 52a, 53a the respective pairs of cylinders would have connections at 44a, 45a branched from the connections 44, 45 aforesaid as is believed will be understood.

What I claim is:

1. In a brake-feeding mechanism of a pilger rolling mill, the combination of a hydraulic forward feeding means operably connected to a carriage for forward movement, a braking means on said carriage comprising a braking plunger and mandrel attached thereto which is movable into a hydraulic braking space on said carriage to brake a forward movement of said mandrel and braking plunger, hydraulic reverse means comprising a hydraulic piston and cylinder connected between a base and said carriage to provide a reverse carriage movement and operative also to take up shock caused by the braking of said plunger in said braking space upon forward release of the mandrel, a hydraulic limiting means comprising a piston and cylinder which are connected with said hydraulic reverse means by a conduit so as to receive hydraulic medium from the said hydraulic reverse means through said conduit during operation of said forward feeding means, stop means operatively associated with said limiting means to stop the same whereby the forward feed of the forward feeding means is maintained constant for each rolling increment of the mill.
2. In the apparatus according to claim 1 wherein said conduit has an adjustable stop valve.
3. In the apparatus according to claim 1 wherein said limiting means has yieldable means attached between said limiting means and a base to provide an additional braking action operative when said limiting means is stopped by said stop means.
4. Braking-feeding means according to claim 1 wherein the said hydraulic limiting means comprises a pair of cylinders oppositely disposed on a common axis and a change-over valve is provided in said conduit between said reverse means and said hydraulic limiting means to transmit hydraulic pressure from the said reverse means alternately to the oppositely disposed cylinders of said hydraulic limiting means and the stop means to determine the stroke of the said hydraulic limiting means comprises a member connected with the pistons of said means and cooperative abutment surfaces lying at a predetermined fixed distance apart on a base.
5. Braking-feeding means according to claim 1 wherein the said hydraulic limiting means comprises a pair of cylinders oppositely disposed on a common axis and a change-over valve is provided in said conduit between said reverse means and said hydraulic limiting means to transmit hydraulic pressure from the said reverse means alternately to the oppositely disposed cylinders of said hydraulic limiting means, and the stop means to determine the stroke of the said hydraulic limiting means comprises a member connected with the pistons of said means and cooperative abutment surfaces lying at a predetermined fixed distance apart, and means for adjusting the said abutment surfaces.
